UNITED STATES PATENT OFFICE.

WILLIAM B. MURRAY, OF WASHINGTON, DISTRICT OF COLUMBIA, ASSIGNOR TO THE MILLER TRAIN CONTROL CORPORATION, OF STAUNTON, VIRGINIA, A CORPORATION OF VIRGINIA.

ELECTRICALLY-OPERATED AND MECHANICALLY-CONTROLLED TRAIN-STOPPING DEVICE.

1,213,891.

Specification of Letters Patent.

Patented Jan. 30, 1917.

Application filed July 27, 1912. Serial No. 711,794.

To all whom it may concern:

Be it known that I, WILLIAM B. MURRAY, a citizen of the United States, residing at Washington, in the District of Columbia, have invented certain new and useful Improvements in Electrically-Operated and Mechanically-Controlled Train-Stopping Devices, of which the following is a specification:

10 The present invention relates to an electrically operated and mechanically controlled device for automatically stopping a train.

15 An important object of this invention is to provide means of the above mentioned character, for use in connection with railway locomotives, street cars, or the like, to automatically set the brakes in times of danger for preventing collisions or other

20 accidents.

25 A further object of my invention is to provide electrically operated means of the above mentioned character, which will apply the brakes when its circuit is opened, thus always operating on the safe side, the brakes being applied if the circuit should get out of order or the source of current fail.

Other objects and advantages of the invention will be apparent during the course 30 of the following description.

In the accompanying drawings forming a part of this specification and in which like numerals are employed to designate 35 like parts throughout the same, Figure 1 is a side view, partly diagrammatic, of the apparatus, Fig. 2 is a side view of the air brake valve and operating means therefor, Fig. 3 is a plan view of the same, and, Fig. 4 is a fragmentary detail view showing the manner in which the spring holds the air brake valve against movement.

In the drawings wherein for the purpose of illustration I have shown a preferred 45 embodiment of my invention, the numeral 1 designates a reciprocatory bar or rod, formed of iron or the like and preferably vertically disposed, as shown. This bar is slidably mounted in spaced brackets 2, which are rigidly connected with the framework of the engine and insulated therefrom. The bar or rod 1 is urged downwardly by a compressible coil spring 3, having one end

attached to a bracket 4 fixed upon the upper bracket 2 and its opposite end attached 55 to a bracket 5, fixed upon the reciprocatory bar or rod 1, as shown. This bar or rod carries at its lower end a shoe 6, adapted for engagement with a ramp 7, which is curved longitudinally in a vertical plane. 60

A switch is provided near the upper end of the reciprocatory bar or rod 1 and comprises a swinging arm 8 formed of insulating material and pivoted, as shown at 9, upon a fixed bracket 10. This arm carries 65 at its free end a contact blade 11, as shown. The reciprocatory bar or rod 1 and arm 8 are flexibly and yieldably connected by a compressible coil spring 12, having the desired degree of stiffness. A stationary metallic strip 13 is arranged near and below the arm 8 and is fixed to a stationary insulation 14. This metallic strip 13 is provided with a stationary contact blade 15, adapted to be engaged and disengaged by the movable or swinging blade 11. It is obvious 70 that the metallic strip 13 is insulated from the frame-work of the engine.

The numeral 16 designates an upstanding solenoid having a downwardly movable core 75. The solenoid 16 is preferably disposed 80 within a casing 18, which is fixedly mounted upon the frame-work of the engine. Rigidly connected with the upper end of the casing 18 is a supporting bracket 19, upon 85 which is pivotally mounted a lever 20 formed of insulating material. This lever 20 is also pivotally connected with the upper end of the core 17 through the medium of a link 21 or other suitably flexible connection. Rigidly secured upon the lever 20 is a metallic strip 22, carrying at its lower end a contact blade 23, adapted to be moved into and out of engagement with a contact blade 24, which is fixed upon the upper end 90 of the metallic strip 13.

One end of the winding of the solenoid 16 is electrically connected with the reciprocatory bar or rod 1 by a wire 25 and the opposite end of this winding is connected or 100 grounded with the frame-work of the engine by a wire 26. The contact blade 11 is electrically connected with the movable contact blade 23 by a wire 27.

The numeral 28 designates a source of current, having one pole connected with the me-

tallic strip 22 by a wire 29 and its opposite pole connected with a wire 30. A wire 31 is connected with the metallic strip 13, as shown.

5 The numeral 32 designates an air brake valve structure, including a casing and valve stem 33, which is turned by a hand-lever 34. This valve structure controls the application of the air brakes in the usual manner and such valve structure is ordinarily operated by the engineer. The hand-lever 34 slidably engages a stationary segmental track 35, the movement of the lever being limited in one direction by an upstanding ear 36 and in the opposite direction by an adjustable stop 37. 10 The hand-lever 34 is moved to actuate the valve structure for applying the brakes, by a retractile coil spring 38. The hand-lever 34 carries a depending lug 39, rigidly connected therewith and adapted for engagement with the free end of a bow-spring 40. As shown at 41, the lower end of the bow-spring 40 is rigidly attached to an end or head 42 of a casing 43. The bow-spring 40 is so tensioned that its upper free end will move out of the path of travel of the lug 39 if not held against such movement.

Disposed within the casing 43 is a solenoid 44, having an upwardly movable core 45. 20 This core 45 has flexible connection with the upper free end of the bow-spring 40 through the medium of a pivotal link 46 or the like. The wire 30 is connected with one end of the winding of the solenoid 44 and the wire 31 is connected with the opposite end of such winding.

25 The ramp 7 may be connected and disconnected with one pole of a source of current 48 by means including a switch 49. The opposite pole of this source of current is connected with a track rail 50 by a wire 51. Any other suitable means, however, may be employed to connect and disconnect the ramp 7 with its source of current.

30 The operation of the apparatus is as follows:—The contact blades 11 and 15 are normally in engagement whereby a circuit is closed for retaining the solenoid 44 energized. As soon as the solenoid 44 becomes deenergized the upper free end of the bow-spring 40 will move downwardly and allow the retractile coil spring 38 to swing the hand-lever 34 for applying the brakes. In this closed circuit current flows from one 35 pole of the source of current 48 through wire 29, metallic strip 22, wire 27, contact blades 11 and 15, wire 31, solenoid 44, and through the wire 30 back to the opposite pole of the source of current. Assuming that the ramp 40 7 has electrical connection with its source of current, as soon as the shoe 6 comes into engagement with the same, a circuit is closed for energizing the solenoid 16. In this circuit current flows from one pole of the source 45 of current 48 through switch 49, ramp 7,

shoe 6, bar 1, wire 25, solenoid 16, wire 26, frame-work of the engine, rail 50, and through wire 51 back to the opposite pole of the source of current 48. By energizing the solenoid 16 the movable core 17 is drawn 70 downwardly and the contact blade 23 moved into engagement with the contact blade 24 prior to the disengagement between the contact blades 11 and 15, which is caused by the elevation of the bar or rod 1. It is thus seen 75 that the circuit for energizing the solenoid 44 remains closed, the same being completed through contact blades 23 and 24 instead of through contact blades 11 and 15. The brakes will not be applied and the engine 80 accordingly allowed to pass the ramp 7.

Assuming that the switch 49 is open so that the ramp section 7 is disconnected from the source of current 48, when the shoe 6 engages said ramp section 7 the solenoid 16 85 will not be energized, whereby contact blades 23 and 24 remain out of engagement. The circuit for energizing the solenoid 44 is opened when the bar or rod 1 is sufficiently elevated to disconnect the contact blades 11 90 and 15. As soon as this takes place the solenoid 44 being deenergized the upper free end of the bow-spring 40 moves downwardly 95 out of the path of travel of the lug 39 and the retractile coil spring 38 swings the hand-lever 34 for applying the brakes.

It is to be understood that the form of my invention herewith shown and described is to be taken as a preferred example of the same and that certain changes in the shape, 100 size, and arrangement of parts may be resorted to without departing from the spirit of the invention or the scope of the subjoined claims.

Having thus described my invention, I 105 claim:—

1. In apparatus of the character described, train stopping means, means to automatically operate the train stopping means when released, means normally preventing the 110 operation of the train stopping means and adapted to automatically move upon being released so that said train stopping means may operate, an electrical device to normally hold the last named means against such automatic movement, a normally closed circuit including a source of current connected with the electrical device, a switch connected in the closed circuit, a mechanically operated structure to actuate the switch, a stationary 115 ramp to move the mechanically operated structure, a source of current having electrical connection with the stationary ramp, and means including an electrical device having electrical connection with the movable structure and adapted when energized to close the circuit upon the opening of the switch.

2. In automatic train stopping apparatus of the character described, automatically 120

operated train stopping means, an electrically operated device adapted when energized to prevent operative movement of the automatically operated train stopping means, 5 a normally closed circuit including a source of current connected with said electrically operated device, mechanically operated means to open the closed circuit, and electrically operated means to close the circuit.

3. In automatic train stopping apparatus of the character described, automatically operated train stopping means, electrically operated means adapted when energized to prevent the operation of the automatically 15 operated train stopping means, a normally closed circuit including a source of current connected with the electrically operated means, mechanically operated means to open the circuit, an electrically operated device 20 to close the circuit at another point and in a shunt around the point where the circuit is opened by the mechanically operated means, and a stationary ramp serving the double function of moving the mechanically operated 25 means and supplying current to the electrically operated device.

4. In apparatus of the character described, train stopping means, means controlling the operation of the same including a circuit, a 20 ramp, a source of current, means for connecting and disconnecting the ramp with and from the source of current, a reciproca-

tory structure to travel into engagement with the ramp and be moved thereby, switch means operated by the reciprocatory structure upon the engagement of the same with the ramp to open the circuit at one point, and electrically operated switch means to close the circuit at another point upon the engagement of the reciprocatory structure 40 with the ramp when the latter is connected with the source of current.

5. The combination with the track rail, of a ramp rail; a vehicle having a controlling device and a magnet for controlling said device; a current supply on the vehicle; a circuit on the vehicle which normally includes the said electro-magnet; a contact on the vehicle to engage the ramp rail and thereby effect a break in the normal vehicle circuit 45 through the electro-magnet; a branch in said normal vehicle circuit between the vehicle current supply and electro-magnet and means for closing a connection from the vehicle current supply through said branch 50 while the vehicle contact is in engagement with a ramp rail.

In testimony whereof I affix my signature in presence of two witnesses.
